UNITED STATES PATENT OFFICE.

ENOS H. SHORT, OF GASSAWAY, WEST VIRGINIA.

MAIL-BAG CATCHER.

No. 907,186.

Specification of Letters Patent.

Patented Dec. 22, 1908.

Application filed January 9, 1908. Serial No. 409,982.

To all whom it may concern:

Be it known that I, ENOS H. SHORT, a citizen of the United States, residing at Gassaway, in the county of Braxton, State of West Virginia, have invented certain new and useful Improvements in Mail-Bag Catchers; and I do hereby declare the following to be a full, clear, and exact description of the invention, such as will enable others skilled in the art to which it appertains to make and use the same.

This invention has relation to a new and useful improvement in mail bag catchers.

The object of my invention is to provide a mail bag catcher which is simple of construction and readily operated as will be described more fully hereinafter.

In the accompanying drawings I have shown in Figure 1 a top view of a mail bag catcher set to catch a mail bag. Fig. 2 discloses a top view showing a mail bag as caught by the catching device. Fig. 3 discloses an enlarged detail of the catching arms as used in my invention. Fig. 4 shows an enlarged detached view of the forked spring as used in my invention. Fig. 5 discloses a perspective view of the plate spring, and Fig. 6 shows an enlarged detail of the pin used to secure the supporting bar.

The object of this invention is to provide a mail bag catcher in which simplicity of design, durability of construction and positive action of the instrumentalities have been kept in view.

Between the door posts 1 of a suitable mail car B is pivotally held the supporting bar 2 having a stop shoulder 3, at one end, while at the opposite end this supporting bar is provided with a perforation adapted to receive the stem of a pin 5 passing through a collar 4 as shown in Fig. 6. Secured to this supporting bar 2 is a crane rod 7 having a terminal ear 9 through which the supporting bar 2 passes, this crane rod being provided with the crook 8 and the handle 10 as shown. The crook 8 is provided with a supporting ear 11, while the crane rod intermediate of its ends is provided with the supporting pins 12 and 13, as clearly disclosed in Fig. 1.

Pivottally mounted upon the supporting pin 12 is a bifurcated curved catching arm 15 having an enlargement 16 provided with a suitable perforation to receive the pin 12 as shown in Fig. 1. Extending from this catching arm 15 is a stem 17 having an ear 18 as is shown. An ordinary coil spring is secured

to the ears 11 and 18. Pivottally mounted upon the supporting pin 13 is a curved forked spring 20 having a terminal eye 21 engaging a pin 22 fixed to the supporting bar 2, as shown in Fig. 1. This forked spring is provided with the crook 23, the spring being continued in a solid portion 24 as shown in Fig. 4 which ends in a lip 25. At the crooked portion this forked spring is provided with the ears a adapted to receive the pin 13. In Fig. 4 the position of the ears a and 22 are clearly disclosed. This spring strides the crane rod 7 as shown in Fig. 1 and also strides the supporting bar 2. Shielding the forked portion 70 forming the crook 23 is a plate spring 26 having the terminal openings 27 and the end opening 28. A suitable screw passes through the opening 28 and into the opening 30 within the forked spring 20 as shown in Fig. 4, while 75 two screws are inserted through the openings 27 and threaded into the openings 23 within the forked spring so that this plate spring is securely fastened to the forked spring. From this it will be seen that the forked spring at 80 its crooked point has a reinforcing spring and it is within this crook that the mail bags lodge.

The operation of my device is as follows: The catching arms are drawn outward against 85 the tension of the spring 19 until the stem 17 is caught by the lip 25 as shown in Fig. 1. Now as the mail bag strikes the forked and plate spring the trigger head is carried out of engagement with the end of the catching 90 arms 15 which are promptly swung around by the retractile spring 19 so that the mail bag is securely held within the catching crook.

Having thus described my invention, what 95 I claim as new is—

1. The combination with a supporting bar, of a crane rod carried by said bar having an operating handle, a catching arm pivotally secured to said crane rod having an extending ear, a spring secured to said ear and said crane rod, a forked spring having a terminal trigger head and a terminal and an intermediate securing ear, a pin carried by said crane rod adapted to engage said intermediate ear, a pin carried by said supporting rod and engaging said terminal ear, and a plate spring secured to said forked spring, as disclosed. 105

2. The combination, with a supporting bar and a crane rod, of a bag-receiving member connected to said bar and rod; a retaining member mounted upon said rod rearwardly 110

of said receiving-member; and means for moving the retaining member forwardly into engagement with a bag caught by said receiving member.

5 3. The combination, with a flexible bag-receiving member, of a retaining member adapted when in inoperative position for engagement with the receiving member, the impact of a bag against said receiving member 10 flexing the latter, to disengage said retaining member therefrom and permit the movement of the retaining member into operative position.

4. The combination, with a flexible bag-receiving member, of a spring actuated retaining member adapted when in inoperative position for engagement with the receiving member, the impact of a bag against said receiving member flexing the latter, to disengage 15 said retaining member therefrom and permit the movement of the retaining member into operative position.

5. The combination, with a bag-receiving member and means for supporting the same, 20 of a retaining member mounted in the rear of the receiving member and adapted for movement forwardly into engagement with a bag caught by the receiving member, when the bag strikes said receiving member.

30 6. The combination, with a bag-receiving member and means for supporting the same, of a spring-actuated retaining member mounted in the rear of the receiving member and adapted for movement forwardly into 35 engagement with a bag caught by the receiving member, when the bag strikes said receiving member.

7. The combination, with a bag-receiving member and a crane rod with which said 40 member is connected, of a spring-actuated retaining member pivoted to said rod in the

rear of said receiving member and including an arm adapted for movement forwardly into engagement with a bag caught by the receiving member when the bag strikes said 45 receiving member.

8. The combination, with a supporting bar and a crane rod, of a bag-receiving member connected with said bar and rod and provided with a trigger; and a spring actuated retaining member pivoted to said rod rearwardly of the receiving member and having one end thereof adapted for engagement with said trigger, the impact of a bag against the receiving member releasing said end from engagement with the trigger, to permit the retaining member to move into engagement with the bag. 50 55

9. The combination, with a bag-receiving member and a crane rod to which said member is attached, of an automatically-operated bifurcated retaining member pivoted to said rod in the rear of the receiving member and straddling the same, said retaining member being adapted for engagement with a bag 60 65 when the latter strikes said receiving member.

10. A device of the character described, having a rotatable catching arm, and a catching device thereon comprising a receiving hook, a retaining finger device pivoted on said arm, spring means to hold said device against the bag after it has been delivered and means for actuating said device by the impact of the bag on its delivery. 70 75

In testimony whereof, I affix my signature, in presence of two witnesses.

ENOS H. SHORT.
